UNITED STATES PATENT OFFICE.

MARK F. MADDEN, OF CHICAGO, ILLINOIS.

FOOTGEAR.

Application filed October 4, 1921. Serial No. 505,287.

To all whom it may concern:

Be it known that I, MARK F. MADDEN, a citizen of the United States, residing at Chicago, in the county of Cook and State 5 of Illinois, have invented a new and useful Improvement in Footgears, of which the following is a specification.

My invention relates to foot-gear for use by persons when lying in bed; and my primary object is to provide for a distribution 10 of the pressure exerted against the side of the foot when lying on its side, otherwise than occurs when the foot is naked, to render the person more comfortable, and when parts of the foot are tender, or sore, to relieve pressure, by the weight of the foot, 15 against such part or parts.

As a premise to the following description it may be stated that even when the foot 20 of a person is in substantially normal condition, the fact that the weight of the naked foot, when lying on its side, is borne by relatively restricted areas of the foot more particularly the ankle-bones and the side 25 of the ball of an outer toe, often produces discomfort to the person, and in this connection it is one of my objects to provide for such distribution of the pressure against the foot that it will be exerted against 30 greater areas thereof than in the case of the naked foot, either only over areas not subjected to the pressure in the case of a naked foot, or over such other areas also those subjected to pressure in the case of 35 a naked foot, the pressure being preferably substantially equalized over those areas which it is intended to take the pressure.

Furthermore most persons suffer afflictions of the feet which produce great 40 comfort and oftentimes distress, especially when they are lying in bed due to the weight of the feet pressing the afflicted or tender portions of the feet, against the mattress portion of the bed. This commonly occurs where the person has corns, bunions, 45 tender skin, especially over the ankle-bones, and other similar afflictions. In this connection it is another object of my invention to provide foot-gear whereby discomfort and distress occurring as above stated 50 will be prevented by providing a construction of foot-gear of such character that these tender and sore portions of the feet will not press against the mattress portion but 55 the pressure against the foot when lying on its side will be exerted against other por-

tions of the foot than the sore or tender portions.

Referring to the accompanying drawing: Figure 1 is a perspective view of a foot-gear embodying my improvements. Figure 2 is a plan sectional view of the same taken through the lower portion of the foot-gear; and Figure 3, a view in sectional elevation of the foot-gear, the section being taken 65 transversely of the structure and showing a foot in rear elevation encased therein.

In accordance with the preferred embodiment of my invention I form the foot-gear of an outer casing, or covering, represented 70 at 4, this casing being preferably of very soft and flexible material as for example silk, and shaped to present the form shown in the drawing, more particularly to present the straight side portions extending 75 from the toe to the heel portion at opposite sides of the structure as represented at 5 and 6.

As hereinbefore stated, the primary purpose of the foot-gear is to distribute the 80 pressure against the foot otherwise than that occurring in the case of a naked foot and when the foot presents sore or tender parts to relieve these parts from pressure and to this end I provide within the casing 85 4 padding 7 of any suitable soft material such as that commonly used as the padding for insoles but preferably so prepared as to be somewhat more fluffy and less liable to become in packed condition, the padding 90 being so disposed in the casing, as shown, that it will form a padding or cushion at each side of the foot for causing the pressure exerted against the foot by the weight 95 thereof when lying on its side to be distributed as desired. It will be understood that the arrangement of the padding will depend on the particular desired distribution of the pressure against the foot. In the construction shown, and by way of example, the padding is formed with a socket, 100 or depressed portion, 8 into which the bunion on the large toe of the foot would extend. It is also formed with a socket, or depressed portion, 9 into which the 105 bunion on the small toe of the foot would extend, and also with sockets or depressions 10 into which the ankle-bones of the foot would extend, the padding preferably extending along opposite sides of the foot to 110 a point above the ankle-bones. Where the structure is to be used on a normal foot

22
where it is desired that the pressure exerted by the foot in lying on its side be exerted against a large area of the side of the foot, including the ankle-bone and the ball of an outer toe, the padding would be so arranged and positioned as to so direct the pressure, preferably to a uniform degree over these areas, and where pressure on any part of the side of the foot is to be avoided, 10 the padding would be recessed as explained, thereby to avoid pressure on such part.

Where the structure is to be used on a foot having tender or sore places such as corns, bunions and tender ankle-bones, pressure on which parts is to be avoided, the depressions in the padding, and hereinbefore explained, would be sufficiently deep to prevent pressure against such parts when the foot is lying on its side, or in other words 20 the sore or tender parts would, in effect, be bridged over by the padding. In all of the examples of use above given it is desired, though not necessary, that the padding be so provided as to cause the pressure to be exerted to a uniform degree throughout the 25 areas which are to receive the pressure.

The padding 7 may be combined with the casing 4 in any suitable manner, it being desired that it be secured in place there- 30 to as by stitching it at intervals to the casing.

It will be understood that by preference the structure will be as light in weight as possible particularly to avoid overheating 35 of the feet and present the minimum resistance to the shifting of the encased feet. To this end the structure is preferably so formed as to present a slit 10 extending from the upper edge of the structure at its 40 rear portion downwardly along the back of the structure thence along the sole thereof to a point closely adjacent the ball of the foot and a slot 11 extending from the upper edge of the structure at its front side 45 downwardly along its front edge to a point closely adjacent the forward extremity of the structure. The structure is thus caused to present a large ventilated area which serves to maintain the foot cool without impairing the structure for the intended purpose above stated.

Any suitable means for holding the structure in encasing position about the foot may be provided, such as for example those 50 shown and comprising a tape 12 which may

be wound about the structure as shown and its free ends tied as at 13.

While I have illustrated and described a particular embodiment of my invention, I do not wish to be understood as intending to limit it thereto as the same may be variously modified and altered and the invention otherwise embodied without departing from the spirit of my invention.

What I claim as new, and desire to secure by Letters Patent, is:

1. In a foot gear, a structure adapted to be applied to, and to extend at opposite sides of the foot comprising a body of padding material internally contoured to fit the sides of the foot, the edges of said body spaced apart at the instep and at the bottom portions for purposes of ventilation, said body having an external form of regular outline adapted to contact substantially uniformly with a supporting surface, whereby pressure of support of the reclining foot shall be substantially uniform over its lower surface, and means to secure the gear upon the foot.

2. Foot-gear comprising a structure adapted to be applied and secured in position on a foot having a sore or tender portion, to extend at opposite sides of the foot, said structure comprising a body of suitable material at opposite sides of the structure so proportioned and shaped as to avoid pressure from the weight of the foot against such tender or sore portion when the foot is lying on its side, said body being slotted along its front, rear and sole portions, and means for holding said body in place on the foot.

3. In a foot-gear, a structure adapted to be applied to, and to extend at opposite sides of the foot comprising a body of padding material internally contoured to fit the sides of the foot, the edges of said body being spaced apart at the instep and at the bottom of the structure practically throughout its length for purposes of ventilation, said body having an external form of regular outline adapted to contact substantially uniformly with a supporting surface, whereby pressure of support of the reclining foot shall be substantially uniform over its lower surface, and means to secure the gear upon the foot.

MARK F. MADDEN.
